DESIGN FOR A DISPLAY RACK

Walton M. Bodine and Walter C. Marshall,
Kansas City, Mo.

Application February 17, 1936, Serial No. 61,212

Term of patent 7 years

To all whom it may concern:

Be it known that we, Walton M. Bodine and Walter C. Marshall, citizens of the United States, residing at Kansas City, in the county of Jackson and State of Missouri, have invented a new, original, and ornamental Design for a Display Rack, of which the following is a specification, reference being had to the accompanying drawing, forming a part thereof.

Figure 1 is a side elevation of a display rack showing our design.

Fig. 2 is an inverted plan view of the display rack.

Fig. 3 is a sectional plan view, taken on line III—III of Fig. 1.

We claim:

The ornamental design for a display rack as shown.

WALTON M. BODINE.
WALTER C. MARSHALL.
